VACUUM TUBE

Walter van B. Roberts, Princeton, N. J., assignor
to Radio Corporation of America, a corporation
of Delaware

Application September 29, 1927, Serial No. 222,696
Renewed September 21, 1934

9 Claims. (Cl. 250—27.5)

This invention relates to the thermionic art and deals more specifically with a vacuum tube designed to be operated from an alternating current source. It has already been proposed to energize the filament of a three electrode vacuum tube from an alternating current source instead of from the usual A battery or its equivalent. While an ordinary tube operating as an amplifier, that is, along the portion of the characteristic which is substantially a straight line, may utilize an alternating current filament supply, such use is not fully satisfactory, and when using the tube so lighted as a detector, that is, when the tube is operating along the portion of its characteristic curve which is either concave or convex, the hum due to the alternating current source becomes so great as to render this scheme impractical. It has been found that the magnitude of that portion of the hum due to alternation of filament voltage varies as the square of the voltage drop across the filament of the tube. Consequently by reducing the voltage drop across the filament the hum generated can be materially reduced. For example, a tube having a filament drop in the neighborhood of 0.8 of a volt has been found to give good results. It is difficult, however, to produce tubes with so small a filament drop which have a sufficient emission, and moreover, there still remains a certain amount of hum when using these tubes in the ordinary receiver set.

My investigation indicates that there are two important factors which govern the hum generated in an alternating current tube. One of these may be called the voltage effect, and the other may be called the magnetic effect.

The voltage effect may be explained as follows:

When an alternating current is flowing in the filament the voltage effective in the plate circuit between the plate and the centre of the filament is a maximum when the filament voltage is a maximum in either direction, and a minimum when the filament voltage is zero. The variation in plate current which this effect acting by itself would cause, would produce a hum in the output having a frequency twice that of the alternating current source. It is not an effect of variations of temperature, but of changes in effective voltage between plate and filament.

On the other hand, the magnetic effect appears to be as follows:

With an alternating current flowing in the filament the magnetic field which it produces alters the paths followed by the electrons, thus caus-

ing the plate circuit resistance to vary, and from this cause the plate current varies inversely as the filament current, that is, when the filament current is a maximum in either direction the plate current is a minimum; and the plate current is a maximum when the filament current is equal to zero. It will thus be seen that the voltage effect and the magnetic effect exert their influence upon the plate current in opposite phase.

I have found that it is possible to cause these two effects to substantially balance each other and thus produce a vacuum tube for alternating current operation which gives a minimum hum in normal use, and my invention consists in the method of and means for accomplishing this result.

These and other objects of the invention will be readily apparent to one skilled in the art from the following description taken in connection with the accompanying drawing in which:

Fig. 1 is a graphical representation of the variations in plate current corresponding to the variations in filament current;

Fig. 2 is a graphical representation of the variations in plate current in accordance with the variations in filament voltage; and

Fig. 3 is a diagrammatic representation of a specific embodiment of my invention.

Referring in detail to the drawing, the vacuum tube 10 is seen to comprise the usual plate and grid elements 11 and 12 respectively. A linear filament 13 suitably designed to have the necessary low voltage drop across its terminals is mounted in the tube 10 and is connected to the secondary of a transformer 14, the primary of which may be connected to any suitable alternating current supply means. The transformer 14 is designed to reduce the voltage from the relatively high value normally available for use, to the low voltage at which the filament is designed to be operated. Connected in series with the filament 13 is a coil 15 which may be wound either interiorly or exteriorly of the vacuum tube and supported in any convenient manner. This coil is designed to increase the magnetic effect of the current flowing in the filament. It will be seen that in view of the series connection between the filament and the coil the current in the coil depends upon the current flowing in the filament, and consequently the magnetic field set up by the coil has an effect in the same phase upon the electron stream as the current flowing in the filament. By properly proportioning and locating this coil 15 it is possible to vary the

magnitude of the magnetic field resulting from the current flowing in the filament in such a way as to obtain a substantial balance between this effect and the voltage effect, thus reducing 5 to a minimum the variations in plate current resulting from alternating current in the filament.

In carrying out the construction of Fig. 3 the magnitude of the magnetic field may be varied by varying the distance of the coil 15 from the elements of the tube, or alternatively the number of 10 turns in the coil 15 may be varied to give the desired adjustment.

It has been found in actual practice that a 15 proper value of the magnetic field in the restricted space between plate and filament may be obtained by a proper design of the filament of the tube, without resorting to special coils or the like, while at the same time producing the desired filament temperature and electron emission. This 20 mode of carrying out my invention cannot readily be illustrated by drawings, as it depends upon the proportioning of the resistance of the filament so that a filament of a given physical disposition will produce a given magnetic field for a given 25 voltage drop. Since it is the voltage variation across the filament which causes the voltage effect, while the current variation causes the magnetic effect, it is the resistance which should be altered, (other things being unaltered) in 30 order to arrive at the desired minimum of hum. Since the arrangement of the filament also determines the effective field, these several factors all have to be considered in the correct design of a tube in accordance with this invention.

35 The correct design of a tube in accordance with the invention is most readily arrived at by the following process:

Being given the grid and plate structure, put 40 in a filament of low voltage, say 1 volt. Connect the tube to some means for observing the presence 45 of double frequency current in the plate circuit. Bring grid and plate returns to the centre of a potentiometer across the filament. Adjust grid and plate potentials to bring the operating point 50 on the straightest part of the grid potential plate current characteristic, such point being known or readily determinable by those skilled in the art. This adjustment makes the voltage effect negligible but does not eliminate the hum effect 55 due to the magnetic field of the filament current. Now increase the negative grid bias gradually until a minimum of hum or double frequency current in the plate circuit (as indicated by the aforesaid means) occurs. If the minimum occurs 60 at substantially the desired operating bias, the filament structure is satisfactory and such that no appreciable hum occurs in the plate circuit during normal operation. However, if the minimum occurs before the desired operating bias is 65 reached, the filament structure is unsatisfactory in that the voltage effect is sufficient to counter-balance the magnetic effect for that value of grid bias where the curvature of the grid voltage-plate current characteristic is less than prevails at the desired operating bias. In other words 70 under the desired operating conditions the voltage effect predominates. Hence the filament should be replaced by one having lower resistance for the same dimensions, or else by a filament of the same wire having less of its length contributing to the electron emission, or by any filament in which the voltage effect is less in comparison with the magnetic effect. By such procedure one 75 satisfactory construction for all around use has

been found to consist of the 201-A tube structure having the resistance of the filament lowered to about 1.5 ohms, the filament being of the oxide coated type so that sufficient electron emission is obtained with voltages well under 1.5 volts. The 5 metal core of the filament is rectangular in cross section and about 2" in length bent in the inverted V shape.

It will readily be understood that the correct 10 relation of internal field and voltage drop may be produced by various specific constructions, and I therefore do not intend to be limited by the 15 details of this disclosure except as defined in the appended claims.

Having thus described my invention, what I 15 claim is:

1. A vacuum tube having a filament, grid and plate, said filament being adapted to be energized from an alternating current source, whereby 20 variations in plate current occur when said tube is operated, and means for magnetically balancing out said variations in plate current, said means being independent of the filament and under control of the current flowing in said filament.

2. A vacuum tube having a filament, grid and plate, said filament being adapted to be energized from an alternating current source, whereby 25 variations in plate current occur during the normal operation of said tube, and means for magnetically generating variations in plate current in 30 opposite phase to said first mentioned variations substantially to reduce said first mentioned variations, said means being independent of the filament and under control of the current flowing in 35 said filament.

3. A vacuum tube having filament, grid and plate electrodes, said filament having a relatively 40 low voltage drop across its terminals and a relatively high current capacity, said tube having within it means other than the filament for creating a magnetic field sufficient to balance 45 variations in plate current resulting from the variations in voltage on the filament.

4. A vacuum tube having a filament adapted to be energized from a source of variable potential, whereby 50 variations in the plate current occur during the normal operation of the tube, said filament being provided with additional means for creating a variable magnetic field sufficiently intense to produce variations in plate current, said last mentioned variations and said first mentioned variations being substantially equal and 55 opposite in phase.

5. A vacuum tube having filament, grid and plate electrodes, said filament having a relatively 55 low voltage drop across its terminals and a relatively high current capacity, said tube having within it means other than the filament for creating a magnetic field sufficient to balance 60 variations in plate current resulting from the variations in voltage on the filament, said means comprising an inductance surrounding the filament and serially connected therewith.

6. A vacuum tube having a filament adapted to be energized from a source of variable potential, whereby 70 variations in the plate current occur during the normal operation of the tube, said filament being provided with additional means for creating a variable magnetic field sufficiently intense to produce variations in plate current, said last mentioned variations and said first mentioned variations being substantially equal and 75 opposite in phase, said means comprising an in-

ductance coil serially connected with the filament.

7. A vacuum tube comprising a plurality of electrodes including a filamentary cathode, and a closely wound coil of wire within the tube envelope coaxially arranged about the cathode and serially connected therewith.

8. A vacuum tube comprising a cathode, a grid electrode surrounding the cathode, an anode surrounding the grid electrode and a coil of wire

surrounding the anode and electrically connected with the cathode within the tube envelope.

9. A vacuum tube comprising a filamentary cathode, grid and anode electrodes coaxially mounted about the cathode, and a cylindrically shaped coil of wire mounted outside the anode and having as its axis the filamentary cathode, and a connection between the cathode and the coil of wire. 5
